UNITED STATES PATENT OFFICE.

CHARLES ALPHAUUS RASCO AND JOHN TOMLINSON TAYLOR, OF AMERICUS,
GEORGIA.

SEAL-LOCK.

SPECIFICATION forming part of Letters Patent No. 654,021, dated July 17, 1900.

Application filed April 21, 1900. Serial No. 13,727. (No model.)

To all whom it may concern:

Be it known that we, CHARLES ALPHAUUS RASCO and JOHN TOMLINSON TAYLOR, citizens of the United States, and residents of 5 Americus, in the county of Sumter and State of Georgia, have invented a new and Improved Seal-Lock, of which the following is a full, clear, and exact description.

This invention relates to improvements in 10 seal-locks particularly adapted for use on freight-car doors; and the object is to provide a seal-lock of simple construction and comparatively cheap to manufacture and in which the seal must be destroyed or broken before 15 the lock can be opened.

We will describe a seal-lock embodying our invention and then point out the novel features in the appended claims.

Reference is to be had to the accompanying 20 drawings, forming a part of this specification, in which similar characters of reference indicate corresponding parts in all the views.

Figure 1 is a perspective view of a seal-lock embodying our invention. Fig. 2 is a front 25 view with a portion of the front plate removed and showing the locking position of the parts. Fig. 3 is a similar view, but showing the parts in unlocked position. Fig. 4 is a section on the line $x-x$ of Fig. 2, and Fig. 5 is a section 30 on the line $y-y$ of Fig. 2.

The lock comprises a casing 1, adapted to be secured to the outer side of a car 2 adjacent to the sliding door 3. Mounted to swing in the casing is a hook-latch 4, having an arm 35 5 extended outward through an arc-shaped slot 6 in the front plate 7 of the casing, and extended upward from this arm 5 is a lug 8, provided with a recess 9, adapted to receive one end of the glass seal 10. The said recess 40 opens upward and outward so the seal may be slipped therein. Extended horizontally from the arm 5 is a perforated lug 11, adapted to receive the hasp 12 of a padlock, the said hasp also passing through a perforation in a 45 lug 13, fixed to the outer side of the front plate 7. The hook-shaped latch 4 is designed to engage with the hook-shaped end 14 of a locking-bar 15, attached to the sliding door 3.

Mounted to swing on the outer side of the 50 front plate 7 is a keeper-block 16, having a recess 17 in its end to receive an end of the

seal 10, as plainly indicated in Fig. 2. Seated in a recess formed in the inner side of the keeper-block 16 is a spring-pressed lug 18, designed to engage in a recess 19, formed in the 55 outer surface of the front plate 7. As will be noted in Fig. 5, the base-wall of this recess 19 is inclined downward and outward, so that when the keeper-block is moved in one direction it will cause the spring-pressed lug 18 to 60 be moved inward.

In operation when the parts of the lock in the casing 1 are in the position indicated in Fig. 3 the door may be moved to its closed position, which will pass the end of the bar 65 15 into the lock-easing, so that the hook-latch may be turned down into engagement therewith, as indicated in Fig. 2. The seal 10 is to be inserted in the recess 17. Then by turning the keeper-block 16 to the position indicated in Fig. 2 the other end of the seal will 70 pass into the recess 9. The spring-pressed lug 18 will pass into the recess 19 and prevent any possible upward movement of the keeper-block, and it cannot be turned downward because of the seal 10 engaging in the recess, and particularly as the stop-block has a forward projection 20 for engaging upon the upper edge of the seal. Of course when the parts are thus placed the hasp 12 of the 75 padlock is to be engaged with the lugs 11 and 13.

When it is desired to open the door of the car, the seal 10 must be broken. Then after removing the padlock the hook-latch may be 85 turned to the position indicated in Fig. 3, releasing the hook end of the bar 15. When it is desired to relock the car with a new seal, the keeper-block may be rotated, as before 90 described.

From the above description it will be seen that this seal-lock is of very simple construction, having no parts liable to get out of order, and the seals being made of glass are 95 very cheap as compared with metal or like seals.

Having thus described our invention, we claim as new and desire to secure by Letters Patent—

1. A seal-lock for a car, comprising a casing, a hook-latch mounted to swing in the casing, a hook-bar designed to be attached to the

car-door and adapted to be engaged by the hook-latch, an arm extended outward from the hook-latch through a slot in the casing, a lug on said arm having a recess to receive one end of a seal, a keeper-block mounted to rotate on the casing and having a recess to receive the other end of said seal, and means for preventing a rotary movement of said block while engaging with the seal, substantially as specified.

2. A seal-lock, comprising a casing, a hook-latch mounted to swing therein, a part carried by a car-door for engaging with said latch, an arm extended outward from the latch through a slot in the casing, a lug extended upward from said arm and having a recess to receive an end of a seal, means for locking the latch in its closed position, a keeper-block mounted to rotate on the casing and having a recess to receive an end of the seal, and a spring-pressed lug carried by said block and adapted to engage in a recess formed in the outer surface of the casing, substantially as specified.

25. 3. A seal-lock, comprising a casing, a hook-latch mounted to swing in the casing, a device adapted to be attached to a car-door for engaging with the hook-latch, an arm extended from said hook-latch through a slot in the

front plate of the casing, a recessed lug extended upward from said arm, a perforated lug extended horizontally from the arm, a perforated lug on the front plate of the casing for registering with the lug on the arm, a keeper-block mounted to rotate on the front plate of the casing and having a recess to receive an end of a seal and also having a forward projection to engage upon the upper edge of the seal, and means for locking said block from upward motion when engaged by the seal, substantially as specified.

4. In a seal-lock, a casing, a hook-latch mounted to swing in the casing and adapted to engage a part carried by the sliding door of a car, a recessed lug carried by said latch, a recessed keeper-block mounted to rotate on the casing, and a glass seal adapted to engage with its ends in the recesses of the lug and block, substantially as specified.

In testimony whereof we have signed our names to this specification in the presence of two subscribing witnesses.

CHARLES ALPHAEUS RASCO.
JOHN TOMLINSON TAYLOR.
